UNITED STATES PATENT OFFICE.

FILLMORE BUSHEY, OF ST. ALBANS, VERMONT.

RAZOR-BLADE SHARPENER.

1,219,914.

Specification of Letters Patent. Patented Mar. 20, 1917.

Application filed September 13, 1915. Serial No. 50,460.

To all whom it may concern:

Be it known that I, FILLMORE BUSHEY, a citizen of the United States, residing at St. Albans, in the county of Franklin, State 5 of Vermont, have invented certain new and useful Improvements in Razor-Blade Sharpeners; and I do hereby declare the following to be a full, clear, and exact description of the invention, such as will enable others skilled in the art to which it 10 pertains to make and use the same.

This invention relates to a razor blade sharpener.

An object of the invention resides in the 15 provision of a machine by means of which a plurality of razor blades may be sharpened simultaneously and which is so constructed that any one of the blades may be removed and replaced while the machine is going at 20 full speed.

A further object of the invention resides in so constructing the machine that the razor blades will be given a movement longitudinally of the sharpening rolls.

25 A further object of the invention resides in so constructing the machine that its operation will be automatic.

With these and other objects in view, such as will appear as the description progresses, 30 my invention comprises the combination and arrangement of parts as set forth in and falling within the scope of the appended claims.

In the drawing:

35 Figure 1 is an elevational view of a machine constructed in accordance with my invention, only a pair of the blade holders being shown for the sake of clearness;

Fig. 2 is a vertical sectional view;

40 Fig. 3 is a section on line 3—3 of Fig. 1;

Fig. 4 is a section on line 4—4 of Fig. 3;

Fig. 5 is a section on line 5—5 of Fig. 3;

Fig. 6 is a side elevation of the machine;

Fig. 7 is a fragmental detail showing the 45 positions of the blade holders;

Fig. 8 is a perspective view of one of the blade holders;

Fig. 9 is a section on line 9—9 of Fig. 1;

Fig. 10 is a section on line 10—10 of Fig. 50 6; and

Fig. 11 is a perspective view of one of the holder clamps.

Referring to the drawing wherein like parts are indicated by like characters 55 throughout the several views:

In the embodiment of the invention shown

in the drawing, I have illustrated a base 1 which is supported upon suitable legs 2. Mounted upon this base 1 is a pair of upwardly extending standards 3 between which 60 sharpening rolls 4 are mounted, the trunnions 5 on one end of which extend through the adjacent standard 3 and have pulleys 6 secured thereto.

In order that these rolls 4 may be rotated so that the adjacent rolls will move in the opposite directions, I have provided a shaft 7 which is rotatably mounted in certain of the legs 2 and has a drive pulley 8 on one end thereof which is adapted to be 65 connected to any suitable source of motion. Secured to the other end of the shaft 7 is a pulley 9. A belt 10 passes over this pulley 9 and thence directly to and over the uppermost pulley 6. The belt then passes around 70 each of the succeeding pulleys 6 in a manner shown in Fig. 6 of the drawing.

Formed on the standards 3 are ears 11 on which arms 12 are pivotally mounted, the said arms being held in position by rods 13 80 as clearly shown in Fig. 6 of the drawing. Connecting the upper ends of the standards 3 is a cross bar 14 on the ends of which arms 15 are pivotally mounted. The arms 12 and 15 are connected together by vertical bars 16 85 at one side of the device. The ends of the arms are bifurcated to form ears 17 between which bearing blocks 18 are pivotally mounted on pins 19. Cross bars 20 are rotatably mounted in these bearing blocks 18. Depending from the ends of the arm 15 at the opposite side of the machine to that on which the bars 16 are located are bars 21 which are connected to the cross bars 20 by means of links 22, which links are rigidly secured to the cross bars and pivotally secured at 23 to the bars 21. Thus the cross bars 20 may move transversely of the machine upon the movement of the arms 12 and 15 or they may be rocked in the bearing 90 blocks 18 for a purpose which will later appear.

Secured to each of the cross bars 20 is a plurality of clamping members 24, each of which is provided at one of its ends with a 100 pair of spaced resilient fingers 25 in which housings 26 are formed. The other end of each of the members is provided with resilient fingers 27. The number of these clamping members may be limited only by 105 the length of the bars 20. Removably mounted in each of the clamping members

24 is a blade holder 28 which is provided with pins 29 adapted to be engaged by the fingers 27 and pins 30 adapted to be located in the housings 26 in the fingers 25. The 5 blade holder is provided with a socket 31 in which the back of the blade is adapted to be engaged and held in position by a thumb screw 32. When the blades are in place in the holders and the holders are in position 10 upon the clamping members, the blades will extend between the rolls 4.

In order that the blades may be moved so that they will engage the rolls which are located beneath them, for a predetermined 15 interval, and then the rolls which are located above them, I have provided a shaft 33 which is mounted in suitable bearings 34 upon the base 1. Secured to this shaft is a drive pulley 35 over which a belt 36 extends 20 which belt also extends over a pulley 37 upon the shaft 7. Secured to the shaft 33 is a sleeve 38 having a cam groove 39 therein. Pivotaly mounted upon a block 40 is a bell crank lever 41 having a pin 42 on the end 25 of one arm thereof, which pin extends into the cam groove 39. Pivotaly secured to the other end of the lever 41 is a link 43 which is connected at its upper end to an arm 44. This arm 44 is connected to the adjacent 30 cross bar 20. Thus as the sleeve 38 rotates the lever 41 will be actuated and the cross bars 20, through the bars 21, links 22 and arms 15, will be moved about their pivots so that the blades will be shifted upwardly 35 and downwardly into contact with the adjacent rolls.

In order that the blades may be moved longitudinally of the rolls while they are in contact therewith, I have extended one of 40 the bars 21 downwardly and have mounted a roller 45 on the lower end thereof which roller rides in the cam groove 39 in the sleeve 38 and moves the arms 12 about their pivots. This movement of the arms will 45 cause the blades to travel backwardly and forwardly across the sharpening rolls.

It will thus be seen that I have provided a machine for sharpening razor blades in which the blades will be moved longitudinally of the rolls and in contact therewith 50 while the rolls are rotating to sharpen the blades. Furthermore, I have so constructed the device that any one of the blades may be removed and replaced without necessitating the stopping of the machine.

While I have illustrated and described a particular embodiment of my invention, it has merely been for the sake of convenience and I do not wish to be limited to that particular embodiment as it is obvious that 60 numerous changes may be made within the scope of the appended claims.

What I claim is:—

1. In a razor sharpening machine, the combination with a plurality of sharpening 65 rolls arranged in superposed relation, of means for supporting a plurality of razor blades in contact with said rolls, means for moving the blades alternately into contact with the adjacent rolls, means for moving 70 the blades longitudinally of the rolls and common means for actuating the two last mentioned means.

2. In a razor sharpening machine, the combination with a plurality of sharpening 75 rolls arranged in superposed relation, of means for supporting a plurality of razor blades so that they will extend between the rolls, means for shifting the blades alternately into contact with the adjacent upper 80 and lower rolls and means for moving the blades longitudinally of the rolls while they are in contact therewith.

3. In a razor sharpening machine, the combination with a base, of a pair of standards extending upwardly therefrom, horizontally arranged sharpening rolls mounted between said standards in superposed spaced relation, horizontally movable arms mounted on said standards, bars connecting 90 said arms, said bars being mounted on horizontal pivots, means on the bars for supporting a plurality of razor blades in contact with the said rolls, means for moving the arms pivotally and means for simultaneously moving the bars pivotally. 95

4. In a razor sharpening machine, the combination with a pair of standards, of sharpening rolls mounted therebetween, arms pivotally mounted on the standards 100 and adapted to swing in horizontal planes, bars rotatably mounted on the arms and adapted to swing in vertical planes at right angles to the planes in which the arms swing, clamping members mounted upon the said 105 bars and razor blade holders detachably mounted on said clamping members.

5. In a razor blade sharpener, the combination with a pair of standards having sharpening rolls mounted thereon, of a 110 frame mounted upon said standards, blade holders mounted upon said frame, means for moving the frame in a horizontal plane and means for simultaneously moving the blade holders in vertical planes at right 115 angles to the planes of movement of the frame.

In testimony whereof, I affix my signature, in the presence of two witnesses.

FILLMORE BUSHEY.
